US0D1067925S

(12) **United States Design Patent** (10) Patent No.: **US D1,067,925 S**
(45) Date of Patent: ** Mar. 25, 2025

(54) **DISPLAY SCREEN OR PORTION THEREOF
WITH GRAPHICAL USER INTERFACE**

- (71) Applicant: **Apple Inc.**, Cupertino, CA (US)
(72) Inventors: **Mani Amini**, San Jose, CA (US);
Chanaka Karunamuni, Cupertino, CA
(US)
(73) Assignee: **Apple Inc.**, Cupertino, CA (US)
(**) Term: **15 Years**
(21) Appl. No.: **29/891,457**
(22) Filed: **May 5, 2023**

Related U.S. Application Data

- (63) Continuation of application No. 29/814,943, filed on Nov. 10, 2021, now Pat. No. Des. 989,796, which is a continuation of application No. 29/740,324, filed on Jul. 2, 2020, now Pat. No. Des. 936,670, which is a continuation of application No. 29/662,909, filed on Sep. 10, 2018, now Pat. No. Des. 889,484, which is a continuation of application No. 29/606,394, filed on Jun. 5, 2017, now Pat. No. Des. 831,039.

(57) CLAIM

The ornamental design for a display screen or portion thereof with graphical user interface as shown and described.

DESCRIPTION

The sole FIGURE shows a display screen or portion thereof with graphical user interface showing our new design. The peripheral dashed broken lines illustrate a display screen or portion thereof, and form no part of the claimed design.
